INVENTOR.
FRANK BASEL.
BY HIS ATTORNEY.

James F. Williams

UNITED STATES PATENT OFFICE.

FRANK BASEL, OF MINNEAPOLIS, MINNESOTA, ASSIGNOR OF ONE-HALF TO PATRICK HALLORAN, OF MINNEAPOLIS, MINNESOTA.

ROOF-VALLEY SHINGLE.

Application filed June 14, 1922. Serial No. 568,167.

To all whom it may concern:

Be it known that I, FRANK BASEL, a citizen of the United States, residing at Minneapolis, in the county of Hennepin and State of Minnesota, have invented certain new and useful Improvements in Roof-Valley Shingles; and I do hereby declare the following to be a full, clear, and exact description of the invention, such as will enable others skilled in the art to which it appertains to make and use the same.

This invention relates to a shingle adapted to be used in the angle or gutter of a roof valley. While the device of the invention may, if desired, be used in the initial construction, the same is particularly designed as a repair device. As is well known to those skilled in the art, the angle or gutters of roof valleys are now commonly provided with a metal portion comprising a strip usually made of tin forming a gutter in the angle of the roof over the edges of which strip the usual shingles are laid. Such metal gutters often rust out or become punctured, thus causing a leaky roof and it is quite an expensive piece of work to tear up the shingles and replace the strip and shingles.

It is an object of this invention, therefore, to provide a shingle device which can be inserted under the shingles and form a new valley gutter.

It is a further object of the invention to provide such a device comprising a piece of sheet material, preferably metal, being bent along a substantially longitudinal center line to fit the roof valley and having its front or upper edge diverging rearwardly or downwardly at each side of said center line.

It is more specifically an object of the invention to provide such a metal device comprising a pair of rhomboid-shaped sections having their sides of equal length joined to form the center line of the device about which it is bent.

These and other objects and advantages of the invention will be fully set forth in the following description made in connection with the accompanying drawings in which like reference characters refer to the same parts throughout the several views, and in which,

Fig. 1 is a perspective view showing a roof having a valley therein;

Fig. 2 is a plan view of the valley portion of said roof.

Fig. 3 is a vertical section of the roof taken substantially on the line 3—3 of Fig. 2;

Fig. 4 is a plan view showing a series of shingles of the invention in overlapped relation;

Fig. 5 is a plan view of one of the shingle devices;

Figure 6 is a front edge view of Fig. 5; and

Figs. 7 and 8 are diagrammatic views showing the method of forming the shingle.

Referring to the drawings, in Fig. 1 is shown a roof of a building having a valley A therein. The standard shingles 1 are placed on the roof having their longitudinal edges directed parallel to the sides of the roof and their transverse or bottom edges extending parallel to the length of the roof, as indicated by the horizontal lines in Fig. 1, and as shown in Figs. 2 and 3. As above stated, it is customary to place a strip 2 of tin or other metal longitudinally of the roof angle forming a gutter, the shingle 1 overlapping the edges of this strip at each side and leaving the central portion thereof exposed.

In accordance with the present invention, a shingle 3 is provided of the general shape shown in Fig. 5, which shingle is adapted to be bent along its longitudinal center line 4. The shingle illustrated is formed with two similar sides which are of rhomboidal shape having one of their sides of equal length common at the center line 4. In placing the shingle in position the sides thereof are bent into different planes along the center line 4 so as to lie flat against the sides of the roof valley. It is evident from the showing in Fig. 5 that the top of the shingle 3 is pointed and when it is desired to repair the roof gutter the shingles 3 are placed in the valley and the upper pointed ends thereof are pushed under the lower edges of the standard shingles 1. The nails fastening the shingles 1 in place are usually placed adjacent the upper portion thereof and such nails are indicated by the numeral 5. The members 3 being pushed up under the shingles therefore do not interfere with these nails. After one of the members 3 is in place at the upper portion of the roof valley another will be placed under the

105
110

next lower succeeding row of shingles, as clearly shown in Fig. 3. The respective members 3 thus overlap each other and form a continuous shedding surface for the water as it runs down the roof. The lower edges of the members 3 also form an angle, as shown in Figs. 4 and 5 and when shingles 3 are in place in the roof valley these edges, when viewed in a horizontal plane are in line with the bottom edges of the shingles, as shown in Figs. 2 and 3. The position of the members 3, after the same are inserted is illustrated in Fig. 4 and, as shown in Figs. 2, 3 and 4, fastening members, usually comprising ordinary nails, are passed through holes in the lower corners thereof firmly securing the same in position and also passing through the standard shingles overlying the same.

20 It will be apparent that the shape of the shingle 3 will vary with roofs of different pitch and the shape of the shingle is determined is follows.

Referring to Fig. 7, assuming the roof is $\frac{2}{3}$ pitch or that it has eight units rise in twelve units extent, the triangle *b* will represent a vertical section of the roof angle. The hypotenuse of the triangle having the sides 8 and 12 is approximately $14\frac{7}{16}$ units. Another triangle *c* is then laid out with a square having a base of $14\frac{7}{16}$ units in length and an altitude of 12 units in length. The strip of material 6 from which the shingles are to be cut, which strip is usually in practice, made about 14 inches wide, is then laid along the hypotenuse of the triangle *c* and the side of the triangle of 12 units in length is continued into said strip to the center line *d-d* thereof. Another line at the desired distance from line *e-e*, thus formed on the strip is made, and one side of the shingle is marked out ready to be cut. If both sides of the roof valley have the same pitch, the other side of the shingle formed by lines *f* may be immediately laid out or if the other side of the roof valley is of different pitch, the side can be determined in the same manner as described. The shingles can then be quickly cut from the strip 6. From the above description it is seen that applicant has provided a shingle having great utility for the purpose intended. A roof gutter can be repaired as shown and

described in less than two hours time, while to repair the same in the old manner by 55 tearing off the shingles and inserting a new roof gutter and then replacing the old shingles with new ones, usually required three or four times as long, to say nothing of the cost of the new shingles. The shingles 60 3 are preferably made of tin, but of course may be made of any desired material which, preferably will be a thin metal.

It will, of course, be understood that various changes may be made in the form and 65 proportions of the device and in the method of producing the same without departing from the scope of applicant's invention, which, generally stated, consists in the matter shown and described and set forth in 70 the appended claims.

What is claimed is:

1. The combination with a roof valley structure comprising a gutter of sheet metal extending longitudinally of said valley, a 75 series of overlapped shingles extending along each side of said gutter and superposed thereon, of a series of overlapped members bent along a longitudinal center line and having diverging top edges, which members 80 are inserted under and in contact with the edge portions of the shingles adjacent each side of said gutter and are superposed in overlapping relation on said gutter whereby a renewed gutter is formed by said overlapping members without removing the shingles or the first mentioned gutter.

2. The combination with a roof valley structure comprising a gutter of sheet metal extending longitudinally of said valley, a 90 series of overlapped shingles extending along each side of said gutter and superposed thereon in contact therewith, of a series of overlapped metal members bent along the longitudinal center line and having diverging top and bottom edges, said members being inserted under the edge of and in contact with said shingles at each side of said gutter and superposed in overlapping relation from the bottom upwardly, whereby a 95 renewed metal gutter is formed by said overlapping members without removing the original shingles or the first mentioned gutter.

In testimony whereof I affix my signature.
FRANK BASEL.
